UNITED STATES PATENT OFFICE.

CHARLES A. BAILEY, OF CROMWELL, CONNECTICUT.

CARTRIDGE.

No. 827,600.

Specification of Letters Patent.

Patented July 31, 1906.

Application filed January 27, 1904. Serial No. 190,829.

To all whom it may concern:

Be it known that I, CHARLES A. BAILEY, a citizen of the United States, residing at Cromwell, in the county of Middlesex and State of Connecticut, have invented a Cartridge, of which the following is a specification.

This invention is an improvement in cartridges, and relates more especially to the class of paper-shell cartridges.

In the usual construction of paper-shell cartridges embodying a metal cap and paper tube considerable inconvenience is sometimes experienced by reason of the metal cap pulling from the paper tube in the operation of extracting such a cartridge from the firearm, and it is now customary to reinforce the connection by means of a thick paper wad. The employment of such a wad is not always effective, however, and it also reduces the size of the powder-chamber, as well as adds to the expense.

It is the object of my invention, therefore, to so construct the metal cap that it will firmly engage the sides of the paper tube in addition to the usual engagement by means of the flange, such engagement at the sides being in the nature of a grip which will pull the paper tube out with the cap and prevent one turning upon the other.

The invention consists in cutting away a portion of the sides of the metal cap and expanding the paper tube, so that the remaining portions of said sides will be embedded in the tube, such remaining portions thereby presenting edges which will impinge directly against the tube and provide the necessary engagement of the parts in removing the same.

In some instance the construction of the metal cap is such as to provide extensions or wings and points or spurs intermediately thereof, all as hereinafter fully described, and the novel features of construction specifically pointed out in the appended claims.

In the accompanying drawings, which form a part of this specification, Figure 1 is an elevation of a paper-shell cartridge constructed in accordance with my invention and showing the preferred form of construction. Fig. 2 is a longitudinal sectional view on the line 2 2 of Fig. 1. Fig. 3 is a similar view on the line 3 3 of Fig. 2. Fig. 4 is an elevation illustrating a modification of the invention, in which the sides of the metal cap are provided with slots.

Similar letters of reference indicate similar parts in all the views of the drawings.

The cartridge-shell is made up, as is usual, of a metal cap A and paper tube B, the former being provided with the usual flange a, and in carrying out my invention the sides of said metal cap are partly cut away, so that the remaining portions will provide extensions or wings, as a', which may be of any configuration desired, and the edges of the cap intermediate these extensions or wings are in the present instance shaped to provide spurs or points a². It is preferable that the shape of the wings or extensions be such as to present transverse edges, as a³, which will impinge against the paper tube to effect the withdrawal of the latter with the metal cap in extracting my improved shell from a firearm. The spurs or points a² will also be embedded in the paper tube, inasmuch as the latter is expanded so that the outer surface thereof will be flush with the outer surface of the metal cap.

In addition to the engagement of the parts by means of the sides of the cap, as hereinbefore explained, it is also purposed to provide the usual engagement by means of the flange a, into which the inner end of the tube is forced.

Obviously any suitable means may be employed for expanding the paper tube after it is inserted in the metal cap, the object being to force the tube out into the open parts of the metal cap, so that the extensions or wings will be embedded therein, whereby such extensions or wings will secure a firm grip on the sides of the tube that will resist both a lateral and longitudinal strain.

Though it is not necessary to employ the usual breech - wad with the construction hereinbefore described, such a wad may be employed, if desired.

In the modification, Fig. 4, the metal cap is cut away at the sides in the form of slots c, and the edges c' may be serrated similar to the edges a² in Fig. 1.

Having thus described my invention, what I claim as new, and desire to secure by Letters Patent, is—

1. A cartridge-shell having a rear reinforce portion with its wall divided longitudinally to render it expandible.

2. A cartridge-shell having a rear reinforce portion with its wall divided on inclined lines producing tapering tongues extending to render it expandible.

3. In a cartridge-shell, a metallic cap having crown projections.
4. In a cartridge-shell, the combination with a metallic cap, of means extending from 5 the open end thereof to embrace the usual paper tube.
5. In a cartridge-shell, the combination with a paper tube, of a metallic cap, means extending from the inner end of the cap to 10 furnish a resilient support for the side of said tube.
6. In a cartridge-shell, the combination with a paper tube, of a metallic cap terminating in a skeleton frame.
- 15 7. In a cartridge-shell, a metallic cap provided with a divided forward portion.
8. In a cartridge, the combination with the paper tube, of a metal cap the sides of which are partly cut away to provide openings, and teeth formed at an edge of said openings, the tube being expanded into said openings and engaged by said teeth, substantially as shown and described.
9. In a cartridge, the combination with 25 the paper tube, of a metal cap the sides of which are partly cut away to provide openings leaving extensions or wings, and teeth formed on the edges intermediate the wings, the tube being expanded into the said openings and engaged by said teeth, substantially as shown and for the purpose set forth.
- 30 10. In a cartridge, the combination with the paper tube, of a metal cap A the sides of which are partly cut away to provide extensions or wings a' having lower transverse edges a^3 , and teeth a^2 formed on the edges intermediate said extensions or wings, the
- tube being expanded into the spaces between the extensions or wings and engaged by the teeth, substantially as shown and for the 40 purpose set forth.
11. In a paper-tube cartridge, the combination with the paper tube, of a metal cap having upward extensions at its sides and 45 said extensions provided at their upper ends with lateral wings, and teeth formed on the edges between such extensions.
12. In a paper-tube cartridge, the combination with the paper tube, of a metal cap having upward extensions at its sides and 50 said extensions provided at their upper ends with lateral extensions or wings, substantially as shown and described.
13. In a paper-tube cartridge, the combination with the paper tube, of a metal cap 55 having inwardly-projecting teeth at its upper edge adapted to be embedded in the paper tube.
14. In a cartridge-shell, the combination of a paper tube, and a metallic cap fitted to 60 said tube and having tongues at its forward end, substantially as set forth.
15. In a cartridge-shell, the combination of a paper tube, and a metallic cap fitted to 65 said tube and having rounded tongues at its forward end, substantially as set forth.

In testimony whereof I have signed my name to this specification in the presence of two subscribing witnesses:

CHAS. A. BAILEY
